UNITED STATES PATENT OFFICE.

WILLIAM WASHINGTON PRAYTOR, OF MOUNT PLEASANT, TENNESSEE.

CAR-LOADER.

SPECIFICATION forming part of Letters Patent No. 600,448, dated March 8, 1898.

Application filed July 8, 1897. Serial No. 643,891. (No model.)

To all whom it may concern:

Be it known that I, WILLIAM WASHINGTON PRAYTOR, a citizen of the United States, residing at Mount Pleasant, in the county of 5 Maury and State of Tennessee, have invented certain new and useful Improvements in Car-Loaders; and I do hereby declare the following to be a full, clear, and exact description of the invention, such as will enable others 10 skilled in the art to which it appertains to make and use the same.

My invention relates to improvements in distributing devices which are to be used especially in distributing the load in the operation of loading cars with granular or pulverulent material—such as grain, phosphate, and the like—and has for its object to provide an apparatus by means of which the material being loaded upon the car may be distributed 15 to the ends of the car from a chute which enters one of the doors at the middle of the car, obviating the necessity of having one or more men stationed within the car to distribute the material with shovels.

20 My invention will be understood by reference to the accompanying drawings, wherein the same parts are indicated by the same letters throughout the several views.

Figure 1 represents a diagrammatic view of 25 my loading apparatus as applied to a box-car, the latter being shown in horizontal section. Fig. 2 represents an enlarged sectional view of the distributing-wheel, the section being taken on the line 2 2 in Fig. 1 and looking in 30 the direction of the arrows. Fig. 3 represents an enlarged detail sectional view taken on the line 3 3 in Fig. 2 and looking in the direction of the arrows. Fig. 4 represents a side view of the pivoted catch shown in Fig. 3 as 35 seen from above in said figure, and Fig. 5 is a detail view showing in side elevation the bracket for supporting the shaft of the paddle-wheel within the car.

40 A represents a box-car of any well-known construction, the same being provided with doorways A⁰ A⁰ midway of its length, as in the usual construction.

45 B represents a platform of any suitable construction, having mounted thereon a pair of brackets B⁰ B⁰, in which a shaft B' is rotata-

bly mounted. Pulleys B² and B³ are keyed upon the shaft B' and are held adjacent to the brackets B⁰ B⁰ in any suitable manner, so that the shaft may slide therethrough without displacing the said pulleys.

55

B⁴ and B⁵ are two loose pulleys, upon either of which the corresponding belt may be shifted without stopping the driving power.

C and C' represent two belts driven from any suitable source of power for rotating the 60 shaft B', the belt C' being crossed.

As an additional support for the shaft B', I prefer to have a vertically-adjustable bracket such as shown in Figs. 1 and 5, which rests upon the floor of the car. This supporting- 65 bracket consists of a block or sill H, having a pair of legs H' H' pivoted to its ends. Upon these legs are provided rack-bars h h, in which engage pivoted links h⁰ h⁰ for holding the legs at the desired angle, but which allow the support to be raised or lowered by varying the inclination of the legs H' H'. The lower ends of the rack-bars h h terminate in sharpened points h' h', which take in the floor of the car 70 and prevent displacement of the support. A bearing-block H⁰ for the shaft B' is mounted 75 upon the sill H, and the said shaft is mounted thereon, as shown. The weight of the material being loaded as it falls upon the paddle-wheel will thus be taken up by this supporting-bracket, and it will be seen that the said bracket may be raised or lowered to suit cars 80 of different heights by adjusting the pivoted legs H' H' as above described.

D represents a wheel which is provided with 85 a solid hub D', preferably of wood, rigidly mounted upon the end of the shaft B' and with side disks D⁰ and D⁰⁰, the latter disk being of a somewhat greater diameter than the former, as shown in Fig. 1. These two disks 90 are rigidly attached upon the ends of the hub-cylinder D'.

A plurality of blades E are pivotally connected at their inner edges to the periphery of the hub-cylinder D', between the said disks, 95 as shown in Fig. 2, and have a limited swing about their pivotal points e, being confined within such limits by angle-irons F F, riveted or otherwise secured to the inner sides of the disks D⁰ and D⁰⁰. The blades E are held in 100

either of their extreme positions by means of spring-catches E' , such as is shown in Figs. 3 and 4, wherein the catch E' is shown as pivoted at or about the middle of its length within a slot d^0 in the disk D^0 . One end e' of this pivoted catch is acted upon by a spring e^2 , mounted upon the outer face of the disk, and the opposite end of the said catch is provided with a protruding portion or lug e^3 , by means of which the said catch may be sprung to release the blade. The inward swing of the arm e' of the catch is limited by a suitable stop, such as shown at e^1 in Figs. 3 and 4.

When in use, the blades E should be turned and locked into a backwardly-sloping position, according to the direction of rotation of the wheel. Thus when the wheel is being rotated in the direction of the arrow, as shown in Fig. 2, the blades will be set to the positions shown in that figure, and when the wheel is rotated in the opposite direction the blades should be set to the other extreme limit of their swing. The reason for having the blades so pivoted that they may be adjusted as above described is to allow of the rapid rotation of the wheel in either direction desired and yet cause the material being loaded to be thrown off from the blades of the wheel, the backward inclination of the said blades in either instance preventing any portion of the material being carried around with the wheel through centripetal force, and it has been found in practice that the material is thrown to the extreme ends of the car much better by giving the blades a slight backward inclination.

The operation of the device is as follows: The car to be loaded is run up opposite the chute X , which is run into the door upon one side of the car, and the shaft B' is extended, carrying the paddle-wheel D into the door upon the opposite side of the car, the parts when ready for operation being approximately in the position shown in Fig. 1, where the lower end of the chute is shown as extending slightly over and above the paddle-wheel D . The shaft B' and the paddle-wheel are then rotated in the desired direction by shifting the appropriate belt to its fast pulley, the blades upon the paddle-wheel having first been set to a backward inclination, as above described. The grain, phosphate, or other material is then allowed to run down the chute X and falls upon the paddle-wheel D as the latter rotates. This rotation of the wheel D will cause the material being loaded to be thrown off to one end of the car, so that the car will be filled from that end toward the middle, as will be obvious. The speed of rotation may be varied at will according to the nature of the material. When one end of the car has been loaded sufficiently, the driving-belt first used may be shifted to its idle-pulley and the outer belt shifted from its idle-pulley to its fast pulley and the direction of inclination of the blades E reversed

to correspond. The shaft and wheel will now be rotated in the opposite direction and the material falling down the chute X will be thrown to the previously empty end of the car and there stowed until the load is complete. When one car has been loaded, the shaft B' and the paddle-wheel D , as also the chute X , are withdrawn from the car, and the loaded car being moved away an empty car is run into place and filled as above described.

I do not wish to limit myself to the precise details of construction herein described and shown, as many modifications thereof might be made which could be used without departing from the spirit of my invention. Thus any suitable arrangement of pulleys and belts for rotating the shaft B' may be used, and any suitable form of catch may be used for holding the pivoted blades in position.

The disk upon the side of the paddle-wheel away from the chute should preferably be somewhat larger than the other disk, as shown, in order to prevent the material running over the end of the paddle-wheel; but this is not absolutely essential.

Having thus described my invention, what I claim, and desire to secure by Letters Patent of the United States, is—

1. In a distributing device of the character described, the combination with a shaft, and means for rotating said shaft; of a wheel having a plurality of blades pivoted to the hub thereof, and means for securing said blades in one of several possible adjusted positions, substantially as described.

2. In a distributing device of the character described, the combination with a horizontal shaft, and means for rotating said shaft; of a wheel fixed upon said shaft, and provided with end disks adapted to prevent the material being loaded thereby from falling off from the ends thereof; and blades pivoted between said disks and having a limited range of adjustment, substantially as described.

3. In a distributing device of the character described, the combination with a shaft and means for rotating said shaft; of a cylinder fixed upon said shaft; circular disks mounted upon the ends of said cylinder; a plurality of blades pivoted upon said cylinder; and means provided upon said disks for allowing a limited range of adjustment to said blades; substantially as described.

4. In a distributing device of the character described, the combination with a shaft and means for rotating said shaft; of a cylindrical hub fixed upon said shaft; a pair of disks fixed upon the ends of said hub; a plurality of blades pivoted upon said hub between said disks; stops on said disks allowing a limited swing to said blades; and catches adapted to hold said blades, substantially as described.

5. In a distributing device of the character described, the combination with a shaft journaled in fixed bearings but being capable of longitudinal as well as rotary movement, and

pulleys upon said shaft for driving the same in opposite directions; of a cylinder fixed upon said shaft; a pair of disks mounted upon the ends of said cylinder; a plurality of blades pivoted upon said cylinder between said disks; angle-irons on said disks limiting the swing of said blades; and spring-actuated catches carried by said disks for holding said blades

in either of their extreme positions, substantially as described.

In testimony whereof I affix my signature in presence of two witnesses.

WILLIAM WASHINGTON PRAYTOR.
